UNITED STATES PATENT OFFICE.

RICHARD GREENLEAF TURNER, OF MALDEN, MASSACHUSETTS.

LOOM.

1,336,545.

Specification of Letters Patent.

Patented Apr. 13, 1920.

Application filed June 12, 1917, Serial No. 174,233. Renewed September 4, 1919. Serial No. 321,980.

To all whom it may concern:

Be it known that I, RICHARD GREENLEAF TURNER, a citizen of the United States, and a resident of the city of Malden, in the county of Middlesex and Commonwealth of Massachusetts, have invented certain new and useful Improvements in Looms, of which the following is a full, clear, and exact specification.

10 The object of this invention is the construction of a loom wherein the weft or filling is not carried on a spool in the shuttle, but is fed continuously from an external supply, whereby the machine can be maintained in uninterrupted action, and a single attendant can look after a considerable number of separate looms.

In carrying my invention into effect, I feed the weft thread vertically into the 20 mid-width of the shed, passing it through an eye in the shuttle to the selvage of the fabric being woven, the shuttle being actuated in the customary manner, thus making the feeding continuous. In rendering the process of thus feeding the weft commercially practical, I find two main features to be essential, the first consisting in providing the warp with harness frames, each one controlling one fraction of the 30 warp threads.

The second important feature comprises means for locking the weft threads at the edges of the growing fabric, and thus forming a selvage thereat.

35 Another important element consists in the substitution of a comb for the usual reed as the means for beating the weft up to the web, such comb being necessary in order to permit the passage of the weft thread 40 from the supply point within the shed to the shuttle.

Referring to the drawings forming part of this specification, Figure 1 is a perspective view of the main elements of my loom, 45 the means for forming the selvage edges not being shown therein. Fig. 2 is a longitudinal section of the shuttle used in my loom. Fig. 3 is a cross section of the same, together with the comb and warp and weft. 50 Fig. 4 is a plan view of the loom on a smaller scale, but with the beater comb removed. Fig. 5 is a sectional side elevation of the same, but showing the beater comb in place. Fig. 6 is a sectional elevation of the 55 weft-feeding means. Fig. 7 is a side view of one of the selvage forming devices.

Fig. 8 is a plan view of parts of the loom showing the selvage forming devices connected therewith.

As shown in Fig. 1, the weft thread 1 is received from a suitable source, as a spool 2, and delivered to the upper end of a vertical tube 3 at whose lower end is a slender tubular elbow 4. This tube and elbow are given an oscillation which may 60 be 90°, more or less, as by means of a segment 5 and a rack 6, the latter being reciprocated synchronously with motion of the shuttle 12, the elbow or arm 4 being preferably always pointed toward the shuttle, 70 even while the latter is in motion. The means for such reciprocation may be a bell crank lever 7 pivotally supported at 9, and connected at its upper end with the rack 6, and at its other arm by a link 10 to any 75 suitable moving part of the machine.

At each side of the shed is a shuttle box 11 and a picker stick 13, each box having slots 15 to prevent interference with the weft thread 1 passing through an eye 14 in 80 the shuttle. To deliver the weft thread to the tube 3 with sufficient freedom, I provide a uniformly rotated disk or table 17 immediately above the level of the tube's upper end, actuated and supported as illustrated in Fig. 6, in a horizontal plane, upon which table the weft is delivered by suitable feed rolls 19, 20 at the rate of its use 85 in the web. Hence, as the thread is taken by the shuttle intermittently, enough slack 90 accumulates upon the surface of the revolving disk or table 17 to be readily given to the shuttle. By having the table revolve, the thread descending thereon from the feed rolls is laid around in a circle on the table 95 instead of accumulating in a mass liable to snarl.

The operation of the loom, aside from the selvage-former hereinafter to be described, 100 is as follows:

The warp threads 21 extending for one half the width of the reed are run through the heddles 22 supported by the harness frame 23, as shown in Fig. 1; the warp threads 24 of substantially equal width are 105 run through the heddles 25 carried by the harness frame 26; one half of the warp threads 27 are run through heddles 29 carried by the harness frame 30, and the other half of the warp threads 27 are run through 110 heddles (not here shown) carried by the harness 31; all the warp being drawn over

the breast-beam 32 and fastened to the cloth beam 33 in the usual manner.

Simultaneously with the blow of a picker stick 13, or slightly preceding it, by which 5 the shuttle 12 is shot through the shed to the opposite shuttle box, the tube 3 and its arm 4 are turned to present the arm between the halves of the shed toward which the shuttle is being thrown. The 10 weft 1 running freely through the shuttle eye 14, a section of the same is laid within the shed the entire width thereof. The instant the shuttle enters its box, the comb 34 swings forward and beats the just-laid 15 weft section firmly against the fabric-edge, immediately returning to its original position.

While the beating is being thus performed, and while the arm 4 is in its illustrated position, the harness frames 26 and 31 reverse 20 their relative positions to lower the warp 24 and elevate the corresponding half of the warp 27. Then the shuttle is thrown to the opposite box; the beater comb advances and 25 retires; the harness frames 23 and 30 reverse, since the arm 4 had moved with the shuttle; the shuttle and arm return; the beater comb advances and returns; the frames 26 and 31 reverse, and so the operation 30 continues.

In the drawings, the warp threads are represented as extending past the arm 4 in perfectly straight lines. As a matter of fact the vertical portion of the tubular arm 35 4 will temporarily spread the nearest threads slightly apart in the upper shed, but as soon as the same threads have descended to the lower shed, they come together again and as they again ascend engage the dents with 40 entire uniformity. Consequently the spreading of the threads by the tube 4 is always between the dents and the heddles, and never between the fabric and the heddles in a manner to leave the central dents unoccupied. 45

While friction will retain the weft thread in place during the weaving, the outer warp threads are liable to ravel out when the fabric is in use, should the process, as thus 50 far described, not be succeeded by some means for forming a proper selvage edge thereon. The selvage forming means which I prefer to employ is illustrated in Figs. 7 and 8, and consists essentially of a single-thread sewing machine adapted to engage 55 the weft thread just outside the warp just before or while the shuttle is making its retreat therefrom, at both sides of the shed.

The type of sewing machine used at each 60 side of the forming fabric is illustrated in Fig. 7, where it will be seen that the needle bar 40, which is vertically reciprocated in a well known manner, is carried in a swinging frame 41 supported by a main frame 42. The 65 needle bar is offset and carries the needle

43 at the outer extremity of the offset or arm 44. Coacting with the needle is a looper 45 suitably turned by means of bevel gears 46 and 47, and a vertical shaft 49 which serves the added function of a pivotal axis 70 for the swinging frame.

Each swinging frame 41 is provided with an arm 50 against which a spring 51 acts to normally retain the needle 43 just outside the outermost warp thread at its side; but as the beater comb 34 approaches to press the newly laid weft thread tightly against the fabric, the fingers 52 carried by the beater frame strike said arms 50 and swing the needle bars and needles outward where they 80 will not be struck by the comb. The instant the beater frame recedes, the needles return to their normal positions, and the needle, at the side from which the shuttle is departing, at once descends into the weft-bend just made, and, with the aid of the looper 53, stitches this weft-bend to those already similarly treated, the two stitchers operating alternately immediately after the shuttle leaves the side of the one operating. 90

I prefer to provide each stitcher with a plate or table 53, a part of which comes beneath the fabric, and a part beneath but to the outer side of the warp, a suitable opening being formed therein for the passage of 95 the needle. I also prefer to form the needle 43 with a slight terminal bend 55 designed for helping to press the weft thread into the growing fabric as the needle descends and stitches it to the preceding bend. 100

With all the weft-bends at each edge of the fabric firmly stitched together, the outermost warp threads are held thereby in place and there can be no unraveling of the cloth.

The depressed edge of each plate or table 105 53 may rest in a rabbet 54 of a plate 56 supported by the shuttle box 11 thereat.

To keep the heddles in proper position on the harness, I prefer to provide a reed 35 of well-known type in front of the harness frames but behind the feed tube 3, as shown in Figs. 4 and 5. 110

Fig. 3 shows the shuttle 12 to be pentagonal in cross section, with its eye 14 near its under face in order to insure against the 115 weft's striking the comb 34; while its face 36 is made to be parallel with the normally located edges of the comb-teeth in order to reduce both wear and friction.

With a loom thus constructed, fabrics can 120 be woven at a greatly reduced expense, especially fabrics such as burlaps whose coarse weft will permit of but a scanty length thereof being carried at a time upon the shuttle-spool of the ordinary frame. 125

With my loom, on the other hand, each loom can be supplied with a weft thread a mile in length or more, and the machine can be run without stop or attention for hours at a time, enabling a single attendant 130

to look after several looms and to give no thought to any until the well-known broken-thread alarm advises him of the break of a thread or of the end of either warp or

5 weft.

While I have thus far tried my loom only in the production of toweling and like coarser forms of fabrics, I do not restrict myself thereto, although I now consider it

10 the main field of my loom.

What I claim is:

1. A loom comprising harness frames carrying warp threads, a shuttle having an eye adapted to be thrown through the shed, and means vertically entering the shed at a point intermediate of its width for delivering a weft thread through said eye to the fabric being woven.

2. A loom comprising harness frames carrying warp threads, a shuttle having an eye adapted to be thrown through the shed, and means vertically entering the shed at a point intermediate of its width for delivering a weft thread through said eye to the fabric being woven, and a beater comb reaching through the upper half of the shed only, when at rest.

3. A loom comprising harness frames carrying warp threads, a shuttle having an eye adapted to be thrown through the shed, and means vertically entering the shed midway of its width for delivering a weft thread through said eye to the fabric being woven.

4. A loom comprising harness frames carrying warp threads, a shuttle having an eye adapted to be thrown through the shed, and a vertical tube descending into the shed at a point intermediate of its width through which a weft thread is delivered to said eye and thence to the fabric being woven.

5. A loom comprising harness frames each carrying warp threads for a fraction of its width, a shuttle having an eye adapted to be thrown through the shed, and a vertical tube descending into the shed at an intermediate point, said tube being provided with a tubular elbow, through which tube and elbow a weft thread is delivered to said eye and thence to the fabric being woven, said elbow being adapted to be oscillated from side to side, two only of the harness frames being adapted to be reversed at a time, and such reversal to occur when said elbow has been swung away therefrom.

55 6. A loom comprising four harness frames each carrying warp threads for one-half its width, a shuttle having an eye adapted to be thrown through the shed, and a vertical tube descending into the shed at an intermediate point, said tube having a rigidly connected member extending horizontally within the shed provided with a laterally elongated eye at its outer end, whereby a weft thread is delivered through

said tube and elongated eye to the eye 65 of the shuttle and thence to the fabric being woven, two only of the harness frames being adapted to be reversed at a time and then only when said horizontal member is swung away therefrom.

7. A loom comprising harness frames carrying warp threads, a shuttle having a transverse eye through it at its midlength, means entering the shed at a point intermediate of its width for delivering a weft 75 thread to said eye and thence to the fabric being woven, and shuttle boxes each having slots for the free passage of the portions of the weft thread at the sides of the shuttle.

8. A loom comprising harness frames carrying warp threads, a shuttle adapted to be thrown through the shed, the shuttle having a transverse eye, means entering the shed at a point intermediate of its width for delivering a weft thread through said eye to the 80 fabric being woven, and means for stitching the weft-bends together to form a selvage edge.

9. A loom comprising harness frames carrying warp threads, a shuttle adapted to be 90 thrown through the shed, the shuttle having a transverse eye, means entering the shed at a point intermediate of its width for delivering a weft thread through said eye to the fabric being woven, and a needle and looper 95 at each edge of the fabric adapted for stitching the weft-bends in place thereat.

10. A loom comprising harness frames carrying warp threads, a shuttle adapted to be thrown through the shed, the shuttle having a transverse eye, means entering the shed at a point intermediate of its width for delivering a weft thread through said eye to the fabric being woven, a beater comb, and a needle and looper at each edge of the 100 fabric adapted for stitching the weft-bends in place thereat, and means for moving the needle and shuttle at each edge of the fabric away therefrom as the beater approaches the same.

11. A loom comprising harness frames carrying warp threads, a shuttle having an eye adapted to be thrown through the shed, means entering the shed at a point intermediate of its width for delivering a weft 115 thread through said eye to the fabric being woven, a needle and looper at each edge of the fabric adapted for stitching the weft-bends in place, a swinging frame carrying each needle and looper, resilient means normally retaining each swinging frame in place for the stitching action, and a beater comb adapted as it approaches the fabric to swing said frames outside its range.

In testimony that I claim the foregoing 125 invention, I have hereunto set my hand this 6th day of June, 1917.

RICHARD GREENLEAF TURNER.
